CLAIM

The ornamental design for a paint trim guide, as shown and described.

DESCRIPTION

FIG. 1 is a perspective view of a paint trim guide showing my new design;

FIG. 2 is a top view of the paint trim guide;

FIG. 3 is a left side view of the paint trim guide;

FIG. 4 is a bottom view of the paint trim guide;

FIG. 5 is a right side view of the paint trim guide;

FIG. 6 is an enlarged front view of the paint trim guide; and, FIG. 7 is an enlarged cross-section of the top view of FIG. 2 of the paint trim guide.

The rear view not shown is a mirror image of the front view. Hatch lines in FIG. 7 depict internal structure not visible from the exterior that do not form part of the design sought to be patented. The handle of the paint trim guide is shown with a symbolic break in its length. The appearance of any portion of the article between the break lines forms no part of the claimed design. The length of the handle shown in FIG. 1 is intended to depict the greatest extent of the claimed design. The lesser lengths of the handle shown in FIGS. 2, 4, 6 and 7 are shown for ease of illustration.
